COMBINED COASTER SET, PLAYING CARD DECKS AND HOLDER THEREFOR

Richard H. Cole, Bloomington, and Erwin A. Frand, St. Paul, Minn., assignors to Minnesota Mining and Manufacturing Company, St. Paul, Minn.

Filed July 30, 1970, Ser. No. 24,228

Term of patent 14 years

Int. Cl. D21—01

U.S. Cl. D34—13

FIG. 1

FIG. 2

FIG. 5

FIG. 3

FIG. 4

FIG. 1 is a perspective view of the left side, front and top of a combined coaster set, playing card decks and holder therefor showing our new design;

FIG. 2 is a top plan view;

FIG. 3 is a rear elevational view;

FIG. 4 is a right side view; and

FIG. 5 is a bottom view thereof.

We claim:

The ornamental design for a combined coaster set, playing card decks and holder therefor, as shown
